ALIGNING DEVICE FOR TUBING

John E. Loeffler, Houston, Tex., assignor to
Thornhill-Craver Company, Houston, Tex., a
corporation of Texas

Application September 30, 1946, Serial No. 700,303

8 Claims. (Cl. 285—20)

1

This invention relates to aligning devices for tubing pairs, such as are used in oil refining apparatus, furnaces, etc., subject to high temperatures and pressures.

It is customary to connect adjacent ends of pairs of such tubing by return bend fittings establishing substantially leak-proof communication therebetween, and it is desirable to prevent movements of the tubing ends relatively to each other, as separation from or approach toward each other, twisting, or the like. This is particularly true where the return bends must be removed periodically to permit removal from the tubes of accumulated coke or like carbonaceous deposits and then replaced. One object of the present invention is the provision of a tube aligning device which will cooperate in maintaining desired tube positions with the return bend fitting, while it joins a pair of tube ends, and will prevent spreading, twisting, or other misaligning movements of the tube ends while the return bend fitting is removed from the tubing.

Another object of this invention is the provision of a return bend fitting and cooperating members, including a tube aligning device, functioning efficiently to maintain impervious and leak-proof joints with the connected tubes indefinitely and irrespective of wide variations in temperatures and pressures within the tubes, thus greatly reducing the fire and other hazards incident to the use of oil refining apparatus, etc.

Other objects and advantages will be apparent from the following description taken in connection with the accompanying drawings showing by way of example a preferred embodiment of this invention, and wherein like reference numerals are employed to designate like parts in the several views.

In the drawings:

Fig. 1 is an end view of a pair of tubes connected by my improved return bend fitting assembly, taken substantially along the line 1—1 of Fig. 2.

Fig. 2 is a side view, taken substantially on the line 2—2 of Fig. 1, parts being broken away and shown in section.

Fig. 3 is a detail view showing the tubes in section, substantially on the line 3—3 of Fig. 2, and the aligning device and return bend fitting in elevation.

Fig. 4 is an end view of my improved aligning device.

Fig. 5 is an elevational view of the aligning device, taken substantially along the line 5—5

2

of Fig. 4, parts being broken away and shown in section.

Fig. 6 is an elevational view, taken substantially on the line 6—6, of Fig. 7, of one of the sealing members cooperating with my improved aligning device and with the return bend, parts being broken away and shown in section, and

Fig. 7 is an end view of the sealing member shown in Fig. 6.

Referring now to the drawings, the reference numeral 10 designates a return bend member and 11 and 12 designate a pair of tubes adapted to be joined by return bend member 10. As herein shown, the tube 11 has been chamfered, at 11A, Fig. 2, and a safe-end 13 welded thereto, the safe-end member being upset at its outer extremity and undercut, as shown at 13A, to form an annular slanting walled groove in the rear face of its upset portion for cooperation with my improved aligning device, as hereinafter pointed out. The forward or end face of such upset portion on safe-end 13 is formed with an annular groove 13B for the reception of a gasket ring 14, the opposed walls of groove 13B preferably sloping in opposite directions with respect to the axis of the safe-end member, substantially as shown in Fig. 2. It will be understood that it is not necessary to use a safe-end, as 13, on the tubes 11 or 12, as the ends of the tubes themselves may readily be upset, undercut and grooved, as desired. However, the use of safe-ends permits the machining, upsetting, etc., to be done in the shop to better advantage, with quick welding of safe-ends of required lengths to existing tubes already extending through and protruding from a furnace, or the like. Ready repairing of tubes from which other return bends have been cut is also possible with the use of safe-ends 13.

With the tube ends ready to receive the return bend assembly members, either because of the welding of safe-ends 13 thereon or otherwise, the aligning device is next positioned thereon. The aligning device herein shown comprises a split anchor member having separable complementary portions 15 and 16 respectively (Figs. 3—5) having their central bridge parts 15A and 16A apertured for the reception of a securing bolt 17. The end portions of both halves 15 and 16 of the anchor members are semi-cylindrical and of substantial axial length (Figs. 2 and 5) to engage and reinforce the tubes 11 and 12, and are machined on their inner peripheries to snugly fit against the outer peripheries of the tubes and upset portion of the safe-ends 13 when drawn together by

the securing bolt 17. The forward curved edge of each semi-cylindrical end portion is machined to provide a forwardly projecting mating angle portion adapted to enter and snugly fit within the undercut annular groove 13A in the rear faces of the upset portions of the tubes respectively. When so positioned (Fig. 2) the split anchor member halves are locked in place on both tubes, assuring that both tube end faces are aligned in the desired relation to each other, usually in a single plane. Then when the securing bolt 17 is tightened, the semi-circular end portions of the anchor member draw the two tubes into the desired axial relation to each other, usually with their axes parallel and in a single plane. The positioning of the anchor member upon the tubes serves to correct any existing misalignment of the tubes, and the correct spacing and alignment of the tubes with their centers in the proper plane is maintained as long as the anchor members are kept tight upon the tube ends.

To aid in positioning the return bend member 10 on the tubes 11 and 12, the anchor member is provided with radial lugs 18 spaced circumferentially around each tube, substantially as shown in Fig. 4. The end walls of lugs 18 are preferably radial, and serve to provide a bearing surface for the nuts or securing members 19 whereby the return bend member 10 is forced toward the tube ends when the nuts 19 are rotated. The legs of the return bend members 10 are each formed with radial lugs 20 (Fig. 2) spaced circumferentially around the periphery of the legs. Some of these lugs are provided with vertical working faces that slope at approximately 9° helical angle and cooperate with the similarly inclined working faces on inwardly extending lugs 19A (Fig. 6) circumferentially spaced around the inner periphery of each nut 19, so that the return bend member 10 is effectively drawn toward the tubes 11 and 12 when the nuts 19 are turned. As best shown in Fig. 6, the lugs 19A are positioned adjacent one edge of nut 19 and the second set of inwardly extending circumferentially spaced lugs 19B are positioned adjacent the opposite edge of the nut. The working faces of lugs 19B are arcuate, however, and cooperate with the arcuate faces of lugs 18 on the anchor member to form bearing surfaces toward which the helical working faces on lugs 19A and 20 pull the return bend 10 when nuts 19 are turned through a partial revolution. The circumferential spacing of the lugs 18 and 20 on the anchor member and return bend respectively permits the passage of nuts 19 longitudinally thereover when the lugs 19A and 19B of the sealing member are positioned to pass between lugs 18 or 20. Then rotary movement of the nuts brings the working faces of its lugs into engagement with those on lugs 18 and 20.

Nuts 19 are partially rotated by bolts 21 passing through apertures in arms 19A and 19C (Fig. 1) extending from the return bend 10 and sealing member 19 respectively. When the nut on bolt 21 is threaded toward the bolt head, the arms 19C will be swung nearer to arms 19A, turning the nut 19 and, through the helical working faces on some of the lugs 19A and 20, forcing the return bend 10 toward the tubes until gasket 14 is seated in the annular grooves in the adjacent faces of the return bend member and tube end 13 (Fig. 2). This seating of the gaskets 14 around each tube end is facilitated by the anchor member, which has previously brought the tube ends into proper aligned positions.

The return bend member 10 may be readily re-

moved whenever desired by merely loosening the nuts on bolts 21 and reversely turning nuts 19. Suitable projections 19D are provided on the nuts 19 for engagement by a suitable tool, as a hammer, should the nuts 19 become stuck from long continued usage in tightened position.

Then, after cleaning the tubes or performing any desired operation thereon, while the return bends are removed, the same or a new return bend member 10 may be quickly installed upon the aligned tube ends. When, for example, a number of return bend members are removed to enable cleaning the entire furnace, still, or the like, on which they have been used, all return bend members may be piled together and, after cleaning, picked up at random and secured upon any pair of tubes. With my improved aligning device it is no longer necessary to carefully mark each return bend and pair of tubes to insure return of each return bend member to its original place joining the same pair of tubes.

As many possible embodiments may be made of the invention without departing from the scope thereof, it is to be understood that all matter herein set forth or shown in the accompanying drawings is to be interpreted as illustrative and not in a limiting sense.

Having described my invention, I claim:

1. The combination with a pair of tubes and a removable return bend for establishing communication between the interior of the tubes, of a tube aligning device comprising an anchor member having separable complementary portions each provided adjacent its ends with semi-cylindrical seating portions adapted to embrace the tube ends respectively and an apertured bridge member connecting said seating portions, and means for drawing said complementary portions toward each other against opposite sides of said tubes with their semi-cylindrical portions embracing the tubes, whereby the tubes are brought into aligned position.
2. The combination with a pair of tubes and a removable return bend for establishing communication between the interior of the tubes, of a tube aligning device comprising an anchor member having separable complementary portions each provided adjacent its ends with semi-cylindrical seating portions adapted to embrace the tube ends respectively and an apertured bridge member connecting said seating portions, means for drawing said complementary portions toward each other against opposite sides of said tubes with their semi-cylindrical portions embracing the tubes, whereby the tubes are brought into aligned position, said means also acting to secure said tubes in their aligned positions.
3. The combination with a pair of tubes and a removable return bend for establishing communication between the interior of the tubes, of a tube aligning device comprising an anchor member having separable complementary portions each provided adjacent its ends with semi-cylindrical seating portions adapted to embrace the tube ends respectively and an apertured bridge member connecting said seating portions, and a bolt engaging the bridge members for drawing together and securing said anchor member portions upon the tube ends.
4. The combination with a pair of tubes and a removable return bend for establishing communication between the interior of the tubes, of a tube aligning device comprising an anchor member having separable complementary portions each provided adjacent its ends with semi-

cylindrical seating portions adapted to embrace the tube ends respectively and an apertured bridge member connecting said seating portions, a bolt engaging the bridge members for drawing together and securing said anchor member portions upon the tube ends, the semi-cylindrical portions of said anchor member being provided with spaced radial lugs for aid in securing the return bend in position connecting said tubes.

5. A tube aligning device as recited in claim 1 wherein said tubes are formed with enlarged upset ends having annular undercut grooves in their rear faces and said semi-cylindrical seating portions of the anchor member are formed with mating angle shoulders on their front edges 15 adapted to fit within said undercut grooves

6. The combination with a pair of tubes and a removable return bend for establishing communication between the interior of the tubes, of a tube aligning device comprising an anchor member having separable complementary portions each provided adjacent its ends with semi-cylindrical seating portions adapted to embrace the tube ends respectively and an apertured bridge member connecting said seating portions, and means for drawing said complementary portions toward each other with their semi-cylindrical ends encompassing the tubes, whereby the tubes are brought into aligned positions, said return bend having spaced radial lugs around each leg portion and said semi-cylindrical seating portions of the anchor member having spaced radial lugs therearound, and rotatable securing members having spaced inwardly directed radial lugs adapted to cooperate with said lugs on both the return bend and cylindrical seating portions for securing the return bend upon the tubes.

7. The combination with a pair of tubes and a removable return bend for establishing communication between the interior of the tubes, of a tube aligning device comprising an anchor member having separable complementary portions each provided adjacent its ends with semi-cylindrical seating portions adapted to embrace the tube ends respectively and an apertured bridge member connecting said seating portions, and means for drawing said complementary portions toward each other with their semi-cylindrical ends encompassing the tubes, whereby the tubes are brought into aligned positions, said return bend having spaced radial lugs around each

5 leg portion and said semi-cylindrical seating portions of the anchor member having spaced radial lugs therearound, and rotatable securing members having spaced inwardly directed radial lugs adapted to cooperate with said lugs on both the return bend and semi-cylindrical seating portions for securing the return bend upon the tubes, the ends of said tubes having enlarged upset portions with annular grooves in their rear faces, and the forward faces of said semi-cylindrical seating portions having shoulders adapted to fit in said annular grooves, rotary movement of said securing members to secure the return bend serving to draw said shoulders into said grooves.

8. The combination with a pair of tubes and a removable return bend for establishing communication between the interior of the tubes, of a tube aligning device comprising an anchor member having separable complementary portions each provided adjacent its ends with semi-cylindrical seating portions adapted to embrace the tube ends respectively and an apertured bridge member connecting said seating portions, and means for drawing said complementary portions toward each other with their semi-cylindrical ends encompassing the tubes, whereby the tubes are brought into aligned positions, said return bend having spaced radial lugs around each leg portion and said semi-cylindrical seating portions of the anchor member having spaced radial lugs therearound, and rotatable securing members having spaced inwardly directed radial lugs adapted to cooperate with said lugs on both the return bend and semi-cylindrical seating 25 portions for securing the return bend upon the tubes, said securing members having apertured arms and said return bend having apertured arms, and bolts extending through the apertures in adjacent arms of the return bend and securing members to effect rotary movement of the securing members when the bolts are tightened.
